UNITED STATES PATENT OFFICE.

HARRY B. GARMAN, OF DETROIT, MICHIGAN, ASSIGNOR OF ONE-HALF TO ROY WILSON,
OF DETROIT, MICHIGAN.

SAW-HANDLE.

1,078,599.

Specification of Letters Patent.

Patented Nov. 11, 1913.

Application filed January 30, 1913. Serial No. 745,217.

To all whom it may concern:

Be it known that I, HARRY B. GARMAN, a citizen of the United States, residing at Detroit, in the county of Wayne and State of Michigan, have invented new and useful Improvements in Saw-Handles, of which the following is a specification.

My invention relates to new and useful improvements in saw handles, and has for its object to provide a device of this character which may be made of any suitable material such as aluminum thereby producing an exceedingly light and a strong handle for use with tools especially saws provided with removable blades.

A further object of the invention is to provide a handle of the class described having a pivoted bell crank lever in one arm of which is mounted one end of a saw blade, said bell crank lever being operated by a suitable lever pivoted to the handle through the medium of a sliding pin and an adjusting screw.

A still further object of the invention is to provide the operating lever with a suitable cam portion which operates with the sliding pin and to so mount said lever that the same will be held in its closed position by the hand of the operator when the saw is being used.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numeral to the accompanying drawing forming a part of this specification, in which—

Figure 1, a side elevation of a saw showing my improved handle applied thereto. Fig. 2, an edge view of the handle. Fig. 3, a longitudinal sectional view of the handle showing the operating or cam lever closed, and having a portion of the saw blade and frame broken away. Fig. 4, a similar view showing the operating lever open and Fig. 5, a perspective view of the bell crank lever.

In carrying out my invention as here embodied, 2 represents a suitable frame having a notch 3 in one end thereof to receive the pin or rivet 4 carried by the saw blade 5.

To the frame is attached by suitable fastening means 6, the handle 7 comprising a body portion 8, having a hand hole 9 therethrough and having an operating lever chamber 10 formed in one edge, said chamber being enlarged at one end as indicated by 11 forming a cam chamber. At one end of the handle is formed a cavity 12 in which is mounted the bell crank lever and adjacent thereto is formed a pin opening 13.

14 represents the bell crank lever having a bifurcated arm 15 producing the saw blade slot 16, said arm being provided at one edge with a notch 17 with which co-operates one of the pins 4 of the saw blade, said lever also has a second arm 18 in which is produced the threaded opening 19 adapted to receive the set screw 20. The third or attaching arm 21 of said bell crank lever is provided with a hole 22 through which passes a rivet or its equivalent 23 for attaching the bell crank lever to the handle within the bell crank cavity 12.

The set screw co-operates with a sliding pin 24 mounted to slide rectilinearly in the pin opening 13. The opposite or inner end of said pin co-operating with the cam 25 formed with the cam or operating lever 26 and having a high and low cam face 27 and 28 respectively, said lever being mounted in the chamber 10 and pivoted at 29 by a shoulder screw or its equivalent. The lever 26 has formed at each end, suitable extensions 30 and 31, the latter being formed with the free end of the lever, the base of said extension being larger than the end of the lever or of the same size as that portion of the handle body with which it co-acts, producing a shoulder 32.

In practice, when it is desired to place a blade in the saw, the operating or cam lever 26 is opened as clearly illustrated in Fig. 4, permitting the sliding pin 24 to co-operate with the lower face 28 of the cam and this permits the bell crank lever 14 to swing to the position shown in Fig. 4, thus permitting the pin carried by one end of the saw blade to register with the notch 17 after the pin on the opposite end of the saw blade has been placed in the notch 3 in the frame. The set screw 20 is then threaded inward until the approximate adjustment has been obtained and the lever 26 is then moved to its closed position as shown in Fig. 1, which causes the higher face 27 of the cam to co-

- operate with the sliding pin 24 which will force said pin outward moving the arm 18 of the bell crank lever away from the handle body which will draw the saw blade taut.
- 5 The movement of the pin 24 need not be as great as illustrated in Fig. 4, since the main object is to relieve the pressure and friction between the pin and adjusting screw so that said adjusting screw may be threaded out-
- 10 ward and permit the bell crank lever to swing. When the saw blade has been inserted and the lever 26 moved to its closed position, said lever may be held closed by the hand, when the saw is being used.
- 15 Of course I do not wish to be limited to the exact details of construction as here shown as these may be varied within the limits of the appended claims without departing from the spirit of my invention.
- 20 Having thus fully described my invention, what I claim as new and useful is—
1. A saw handle, a body portion, a bell crank lever pivoted to the body portion, said bell crank lever having means to receive the 25 end of a saw blade, a cam lever pivoted to the body and seating therein, and a sliding pin for transmitting motion from the cam lever to the bell crank lever.
  2. A saw handle consisting of a body portion provided with a hand hole, an operating lever chamber, a bell crank cavity and a pin opening, a bell crank lever having means to receive the end of a saw pivoted in the bell crank cavity, an operating or cam 35 lever pivoted in the lever chamber and a pin mounted in the pin opening for transmitting motion from the operating or cam lever to the bell crank lever.
  3. A saw handle consisting of a body portion provided with a hand hole, an operating lever chamber, a bell crank cavity and a pin opening, a bell crank lever having a bifurcated arm with a notch therein to receive a pin carried by a saw blade, a sec- 45 ond arm having a threaded opening there-
- in, and another arm having a rivet opening therein, said bell crank lever being mounted in the bell crank cavity, a rivet for pivoting said bell crank lever in position, a set screw mounted in the threaded opening 50 in one of the arms of the bell crank lever, an operating lever pivoted in the lever chamber and a sliding pin mounted in the pin opening, coöperating with the operating lever and the set screw for transmitting motion 55 from said operating lever to the bell crank lever.
4. A saw handle consisting of a body portion provided with a hand hole, an operating lever chamber, a bell crank cavity and a pin opening, a bell crank lever having a bifurcated arm with a notch therein to receive a pin carried by a saw blade, a second arm having a threaded opening therein, and another arm having a rivet opening therein, 60 said bell crank lever being mounted in the bell crank cavity, a rivet for pivoting said bell crank lever in position, a set screw mounted in the threaded opening in one of the arms of the bell crank lever, an operating lever having an extension formed at each end thereof, the extension formed with the free end of the lever being greater in size at its base than the body of the lever thereby producing a shoulder which coöperates 65 with the handle body, said lever being pivoted in the lever chamber, a cam having a high and low face formed with the operating lever and a rectilinearly sliding pin mounted in the pin opening coöperating 70 with the cam and the set screw for transmitting motion from the operating lever to the bell crank lever.
- In testimony whereof, I have hereunto affixed my signature in the presence of two 75 subscribing witnesses.
- HARRY B. GARMAN.
